UNITED STATES PATENT OFFICE.

KENNETH HOWIE, OF NORRISTOWN, PENNSYLVANIA, ASSIGNOR TO WILDMAN MFG. CO., OF NORRISTOWN, PENNSYLVANIA, A CORPORATION OF PENNSYLVANIA.

NEEDLE-SELECTOR JACQUARD FOR KNITTING MACHINES.

Application filed April 5, 1927. Serial No. 181,088.

In application for Letters Patent of the United States filed by me May 19, 1926, No. 110,164, I disclose a jacquard or pattern mechanism for a knitting machine comprising a series of unattached toothed plates arranged in a stack or stacks, which plates are individually moved up to the needle bed to control the operation of knitting or tucking on a series of needles embraced between the 10 ends of the series of teeth on the plates, each plate, after being used, being restored to the column or stack of plates to take its place in the series for presentation to the needles in the order prescribed.

15 One improvement in the present invention consists in constructing the plate magazines so that they, with the series of plates carried thereby, may be handled as one body. The magazines are removably attached to 20 the machine so that any one of them may be removed. They are adapted to hold the plates in proper order when so removed, so that they, together with the series of plates, may be returned to the machine as one body 25 and secured in place.

Other features of improvement will appear from the following description and from the claims.

In the accompanying drawings:—

30 Figure 1 is a vertical sectional view of a portion of the machine showing one of the magazines in its relation to the needle bed or cylinder.

Fig. 1^a is a detail view of one of the catch 35 supports for the plates.

Figs. 1^a and 1^b are detail views of a pair of plates in edge view showing marks of identification in respect to which of the several stacks the plates belong.

40 Fig. 2 is a front view of one of the magazines in its relation to the parts of the machine which support it.

Fig. 3 is a plan view of one of the magazines showing plates in dotted lines and 45 stops for the plates.

Fig. 4 is a bottom plan view of certain guide rails for the magazines and illustrating one of the stops for the upper plate of the stack when moved up to the needle bed.

50 Fig. 5 is a view in section of the rails and stop of Fig. 4, looking in the direction of the arrow and on the line 5—5.

Fig. 6 is a view of one of the magazines removed and in section.

Fig. 7 is a detached view of one of the 55 toothed plates.

Fig. 8 shows a plate lifter operating cam.

The magazines comprise vertical guides 24^x which control and guide the plates in their upward movement at the column B. 60 Other vertical guides 24 direct the plates in their downward movement after having been retracted from their operative position against or near the cylinder, and there are also guides 55 which also aid in properly 65 directing the plates downwardly, these latter guides nullifying any tendency for the plates to tip, as they drop vertically onto the stacked plates of the outer column B'.

As shown in the plan view, Fig. 3, there 70 are also vertical rails 60 having faces at 60^a of substantially 45° angle to the side walls 25 of the magazine, these faces also serving as guides for the plates in their dropping movement, conforming as they do 75 to the angular front portions 11 of the plates. The plates have notches at 10^a in their rear edges to accommodate the vertical supplemental guides 55. The upper ends of the rails 60 serve to guide the plates 80 in their retracting movement from their innermost to their outermost positions and hold them from dropping until they have been brought to a position where their side 85 notches register with the vertical guides 24.

These guides 24, 60 and 24^x are attached to the side walls 25 of the magazine and these side walls are connected together by a cross piece a, which is attached thereto by screws 33^x. This cross piece makes a one body construction, together with the side walls 25 and their attached vertical guides, so that the magazine thus provided can be handled as one body, and this is true whether the magazine is empty or full of plates.

In order to mount this magazine (of which there are four in the present machine, like the application above referred to) upon the machine, it has attached to the lower edges of its side walls runners 34 having 100 ribs or flanges 35 adapted to be slid into parallel guide grooves 36 of the lower magazine carrying plate 37. This plate, in the present machine, moves with the needle bed.

It will be understood that the invention is not limited to that type of machine in which the needle bed moves and the cam box is stationary. Said plate is hung from an upper or ceiling plate 28 by the standards or hangers 25^a bolted and screwed to the lower and upper plates. The runners are attached to the side walls 25 of the magazine by screws 25^a passing through upstanding flanges 34^a on the runners, and embracing the lower edges of the side plates. These runners also have horizontally extending bases or flanges 24 which afford supports upon which the columns of plates rest and 10 along which said plates are advanced one by one inwardly from column B' to column B of the stacked plates. The lower ends of the vertical guides 24, 24^a and the rail 60 are in a plane slightly above the platform 20 or support afforded by the horizontal upper surface of the runners, the crevice thus provided being of about the thickness of a plate, so that the lowermost plate of column B' can be advanced inwardly with its ends 25 passing through these crevices to the column B. This magazine has the upper edges of its side walls entering grooves in guide rails b, which rails are provided with ribs entering grooves in the upper rotary magazine 30 carrying plate. These rails have flanges c which afford guides and supports for the pull pawl carrier 26^a, which in turn affords support and guidance for the push pawl carrier 19, the pull pawls being 26 and the push 35 pawls 17.

The upper guide and supporting rails just described are secured to the ceiling plate 28 of the magazine organization by screws d passing through said rails and up into the 40 said ceiling plates.

When a magazine is inserted into place, it is fixed in position by thumb screws e passing down through the runners into the lower plate 37 of the magazine organization. 45 The magazine can be filled before insertion and once inserted, it remains in place until it may be necessary to remove it for inspection or repair.

The plates are pushed inwardly from the 50 bottom of the column B' to a position beneath the column B by pusher bars or pawls 33 consisting of bars fixed in recesses of the lower movable carrier block 33^a, which moves in a guide-way formed by the lower 55 plate 37 and the horizontal flange of the runner 34 of the magazine. These bars project above the block about the thickness of a plate, to engage the lowermost plate of column B' resting on the supporting surface 24^a of the runner. This carrier block has a 60 roller 40 extending into a cam groove 41 in the lower fixed cam plate 41^a, which is fixed to the frame of the machine by a bracket or arm 41^b, so that as the magazine organization rotates with the needle cylinder, the car-

rier block will be reciprocated radially of the machine by its roller running in the said cam groove.

When the plate has been moved inwardly into position beneath the column B it is elevated by a lifter 42 having a roller 44 running upon a fixed cam 41^c which is secured to the lower cam plate 41^a. This lifter consists of a platform 42 on the inner end of the arm 42^a which is seated in a recess at its 70 outer end in the lower plate of the magazine organization, and which, as above described, is hung from the upper plate by the hangers or standards. The arm is held by a stud 42^a extending up through a slightly enlarged 75 opening of the arm so that said arm can have up and down swinging movement.

After a toothed jacquard plate is fed over the platform of this arm, which is then down, the roller on the lower side of the 80 platform, running over a high part of the fixed cam, will elevate the lifter and raise the same so that the plate thereon will be moved up against the bottom of the column 85 B of the stacked plates, this lifting action 90 also effecting the raising of the entire column of plates a distance equal to the thickness of a plate so that the new plate will rise above the spring catches f and will be held up thereby, together with the now elevated entire column of plates. These spring 95 catches serve to hold the plates of the column B elevated above the plane of movement of the next plate which is to be moved from beneath column B' to a position beneath the 100 column B. This space is free, the elevating or lifting platform now being down, that is, when the next plate is advanced inwardly from column B' to column B.

The sequence of operations is that the 105 lifter is down, and column B is resting on catches, leaving a free space above lifter and below catches for the feeding in of a new plate from column B'. This now takes 110 place, whereupon the lifter elevates this new plate above the catches and of course in doing so, it elevates the whole stack. This is done at cam rise X. The upper plate is now withdrawn by the pull pawls to fall down on column B'. The lifter now rises at 115 the second cam incline X² and presses the whole column up against the ceiling. This means that the ends of the uppermost plate are pressed up against the edges at b¹ of upper guide rails b. This may take place, i. e., the upward pressure, either simultaneously with or after the upper plate has been pushed inward against the needle cylinder.

In any event, it holds the toothed plate 120 while the jacks are operating thereagainst. After this action takes place, the lifter falls.

The said uppermost plate is fed by the 125 pusher pawls up to the needle bed. Here said plate is in position so that as the needle jacks 3 rise they will engage the teeth of the 130

plate, provided a tooth lies in the path of the cam edge 12 of the jack. Such jack, which engages a tooth, as just mentioned, will be buried in the groove 14 when it has been 5 lifted by the cam 6 part way up.

Those jacks which are buried in their grooves will not operate their corresponding needles, which will tuck, but those jacks which find spaces between the teeth of the 10 plate in line therewith will pass up through these spaces, or rather these cam inclines will do so, with the result that these jacks will not be disengaged from the cam 6 and buried in their grooves, but will perform their full upward strokes under the action of said cam 6, thus moving the corresponding needle high enough to be engaged by the needle advancing cam for knitting, as set forth in the application referred to.

20 In order to provide stops against which the uppermost plate of the stack will strike when advanced from the stack to the circle of jacks, I provide brackets 7 screwed to the ceiling of the machine frame, i. e., to the 25 underside of the plate 28, which bracket has a flange 8 extending at an angle of 45° between the adjacent or meeting ends of the upper guide rails. These flanges 8 form stops, which limit the inward or advance 30 movement of the toothed plates and prevent them from striking the needle cylinder and scoring it.

Other stops are also provided for arresting the plates when they reach proper position 35 beneath the stack B. These stops consist of blocks 9 having upstanding portions 10 in the path of the plates when they are moved from the column B' to position beneath the column B. These stops present faces inclined at 45° to the direction of movement of the plates and the inclined edges 11 of the plates come against these in the arresting 40 action. These stop members are screwed at 13 to the plate 37.

45 The guides 55 will serve as stops against outward displacement of the lowermost plate of column B'.

In Fig. 1^b is shown a single mark of identification at m. This may consist of a 50 notch as shown in dotted lines in Fig. 3. All the plates which have this mark belong in the same stack. Fig. 1^c shows a plate which belongs in another stack and to identify this plate it is provided with two notches 55 m¹ similar to the notch m. These notches are found in the rear edge of the plate. By this means any plate, upon inspection, can be identified as belonging to either one stack or the other.

60 I claim:

1. In combination with a needle bed, a stack of unattached toothed plates for controlling the action of the needles, means for moving said plates individually from the 65 stack to needle controlling position at the

needle bed and for retracting said plates individually to take their places in the stack, and a magazine carrying the stack of plates removably mounted on the machine, to be handled with said stack of plates as one body 70 in placing it into or removing it from position in the machine.

2. In combination, a needle bed, a series of plates stacked in two columns, means for moving the lowermost plate from one column to a position beneath the other column, 75 means for moving the uppermost plate of the last mentioned column to needle controlling position, and for retracting said plates to position above the first mentioned column, a lifter for the plates, and a magazine removably mounted on the machine and carrying the two columns of plates, said plate moving means being supported independently of the magazine.

3. A knitting machine according to claim 1, having guide rails on which the magazine is slidably mounted for placing or removing.

4. A knitting machine according to claim 1 having upper and lower plates, guide rails removably attached to the upper plates, guide grooves in the lower plate, said magazine at its upper part slidably engaging the rails and having runners slidably engaging 95 the grooves, substantially as described.

5. A knitting machine according to claim 1 in which the magazine is made up of two side walls connected rigidly together by a cross brace, and having vertical guides on 100 said side walls for the plates and having lower rails upon which the plates are supported and slide, substantially as described.

6. A knitting machine according to claim 1 in which the magazine is made up of two side walls connected by a cross brace, and vertical guides carried by said cross brace for engaging notches in the rear edges of the plates for preventing them from tipping, substantially as described.

7. A knitting machine according to claim 1 in which the removable magazine is slideable in guides attached to the frame, said guides having guide flanges for the means which move the plates, substantially as described.

8. In combination in a knitting machine, a series of unattached toothed plates for controlling the operation of the needles, means for moving the plates individually to and from a stack, said means including a device for moving the plates into position beneath the stack, a lifter for moving the plates individually against the bottom of the stack, and detent means for receiving the plates from the lifter and for supporting the stack above the plane of movement of the said plate moving device, substantially as described.

9. A knitting machine according to claim 130

8 in which the device for moving the plates beneath the stack consists of unyielding bars or shoulders engaging the plates.

10. In combination with a needle cylinder,
5 unattached toothed plates for controlling the operation of the needles, means for moving said plates up to and away from the needle cylinder, guides for said plates, and stops adjacent the cylinders against which
10 the front edges of the plates abut, to prevent contact of said plates with the needle cylinder, substantially as described.

11. In combination, a needle cylinder,

toothed plates for controlling the operation of the needles, magazines for said plates arranged on different radii, means for moving the plates to and from the cylinder, and stops to arrest the inward movement of the plates, and prevent them from striking the cylinder, said stops being arranged between adjacent magazines, each stop serving two of said magazines, substantially as described.

In testimony whereof, I affix my signature.

KENNETH HOWIE.
